UNITED STATES PATENT OFFICE

HENRY B. PETIT, OF DETROIT, MICHIGAN, ASSIGNOR TO GEORGE M. HOLLEY, OF DETROIT, MICHIGAN

CARBURETOR

Application filed December 3, 1926. Serial No. 152,324.

This invention relates to an improved carburetor. The object of this carburetor is to provide means for providing the most suitable mixture ratio for the varying conditions 5 of air flow and specifically to provide means whereby the ratio of fuel to the air can be increased conveniently at all air flows to meet the requirements of the engine without disturbing the most economical fuel adjustment 10 for normal conditions.

The figure shows more or less diagrammatically a cross sectional elevation, all the parts being so arranged as to be visible in one plane. (Actually, in the manufacture of 15 the device, the various nozzles and passages would be located in other planes).

In this figure, *a* is the air entrance, *b* is the mixing chamber, *c* is the mixture outlet, *d* is a throttle valve located therein, *f* is the float 20 and *e* is a float chamber connected to the casting containing the mixing chamber in the well known manner. *i* is an extension downward from the casting containing the mixing chamber in which extension the nozzles are 25 arranged and by which extension the float chamber is connected to the mixing chamber *b*.

g is the fuel entrance to the nozzle passages controlled by the needle valve *h*, only a portion 30 of which is shown. *j* is the main fuel nozzle provided with a plurality of perforations *k* and also, with a group of orifices marked *o*. The series of perforations *k* are located at different levels and communicate 35 with the atmosphere through the passage *l*. The group of orifices *o* communicate with the atmosphere through the passage *m*, as shown by the arrows. The nozzle *j* discharges into the mixing chamber *b*, being located at the 40 point of maximum constriction (greatest air velocity).

The passage *p* provides the low speed fuel for running the engine, and is connected with another passage *q* which supplies fuel 45 through a restriction *r* to the chamber *y*. The chamber *y* discharges fuel and air through *s* into the mixture outlet *c* adjacent to the lip of the throttle *d*. The chamber *y* is air bled at *t*, which is a fixed opening, and 50 through *u* and *z*, the flow through which is

controlled by the needle valve *v*. This needle valve *v* thus constitutes the low speed adjustment.

An additional high speed fuel passage *n* is provided. This passage *n* is supplied 55 with fuel independently of the fuel metered at the orifice *g* by the needle valve *h*.

The additional high speed fuel in *n* is regulated by the size of the plug *x*, but chiefly by the size of the fuel outlet *w*, which is smaller 60 than *x*. This additional high speed fuel outlet is located in the air entrance *a*.

Operation.—The provision of the additional high speed fuel orifice *w*, the passage *n* and restriction *c* is the chief novel feature 65 in this carburetor. When running at closed throttle position, fuel flows from the float chamber *e* through the orifice *g* and through *p*, *q*, *r* and is discharged through *s*, being aspirated at *s* by the air from *t* and *u*, the flow 70 through *u* being controlled by the needle *v* which controls the orifice *z*. The operation of the main fuel nozzle *j* is as follows:—

Fuel flows from *e* through the passage in *j* and discharges into the mixing chamber *b*. 75 Enroute it is atomized by air drawn in through *m* and *o* and subsequently as the speed of the engine increases, by air drawn in through *l* and *k*. A shoulder on the nozzle *j* prevents any direct communication between 80 the two passages *l* and *m*, except through the center passage *j*. By providing liberal openings to the passages *l*, *k* and *m*, *o* it is obvious that the mixture at high air velocity will tend to become excessively lean, or to become "over 85 compensated" as it is colloquially called, and this tendency is compensated for by the provision of the orifice *w*.

It will be noted that the orifice *w* is located at a considerable distance (1" or more) above 90 the level of the fuel in the float chamber *e*. There will therefore have to be a greater depression in *a* than 1" of gasoline before the nozzle *w* comes into operation. The specific period in the operation of the engine at which 95 *w* starts to flow is determined, therefore, by the diameter of the air entrance *a*. The depression, however, in the air entrance *a* tends to increase progressively as the air speeds increase, and the area of *w* is arranged to 100

correct the above mentioned tendency of the fuel nozzle j to lean out.

When the choke valve a' in the air entrance a is closed, as shown in the dotted lines, a very much larger depression is created in the air entrance a , and quite a large flow of fuel issues from w which acts as a primer. This ensures ample fuel for starting. It will also be noticed that a small movement of the choke valve a' creates a slight depression in the air entrance a , so that such a movement of the choke valve a' which would hardly disturb the flow through the nozzle j due to its atmospheric bleeding through $l m o k$, or the flow through $p q$ and r , will cause a considerable fuel flow through w for the purpose of facilitating cold engine operation, and then I have provided delicate and convenient means for adjusting the mixture when driving away with a cold engine, and still retained the characteristic compensating feature of the air vented nozzle. The provision of nozzle w eliminates the necessity for unduly restricting the vents $l m$ by mechanical means which have heretofore been used.

In order to make the disclosure complete, I give the following dimensions, which I have found satisfactory. With mixture outlet e equal to a $1\frac{1}{16}$ " circle, and an air entrance a equal to a $1\frac{1}{4}$ " circle, and the minimum area of the mixing chamber b equivalent to $\frac{1}{16}$ " in diameter, I have found that the bore of the main nozzle j should be $1/8$ ". The diameter of the perforations k should be, 3 upper #79 drill and 3 lower #50 drill, there being six of them. The size of the 4 orifices o should be #52 drill. The additional outlet w should be #60 drill, and w should be located 1" above the level in the float chamber e . This particular installation I have found suitable for a Ford Model T engine.

What I claim is:—

1. In a plain tube carburetor having an air entrance, a mixing chamber of Venturi form and having a constant area, a constant level fuel supply chamber, a mixture outlet and a throttle valve therein, an air vented fuel nozzle discharging into the Venturi mixing chamber, an unvented nozzle discharging into an unrestricted portion of said air entrance, and a choke valve located therein on the atmospheric side of said additional nozzle, the unvented nozzle being located a considerable distance above the level in the constant level fuel supply chamber, and being independently fed therefrom.

2. In a carburetor having an air entrance in free communication with the atmosphere, a mixing chamber of Venturi form and having a constant area, a constant level fuel supply, a mixture outlet and a throttle valve therein, an air vented fuel nozzle discharging into the throat of the venturi, an unvented fuel nozzle discharging into an unrestricted portion of said air entrance and hav-

ing an independent communication with said fuel supply chamber whereby additional fuel may be fed in increasing quantities at the higher air velocities only.

3. In a plain tube carburetor having an air entrance, a mixing chamber of Venturi form and having a constant area, a constant level fuel supply chamber, a mixture outlet and a throttle valve therein, an air vented fuel nozzle discharging into the Venturi chamber, an additional nozzle discharging into an unrestricted portion of said air entrance, the additional nozzle being located a considerable distance above the level in the constant level fuel supply chamber, and being independently fed therefrom.

In testimony whereof I affix my signature.
HENRY B. PETIT.
